UNITED STATES PATENT OFFICE.

LOUIS SCHULTZ, OF NEW YORK, N. Y., ASSIGNOR TO LOUISE SCHULTZ, OF SAME PLACE.

STOP-MOTION FOR SEWING-MACHINES.

SPECIFICATION forming part of Letters Patent No. 602,876, dated April 26, 1898.

Application filed December 16, 1896. Serial No. 615,899. (No model.)

To all whom it may concern:

Be it known that I, LOUIS SCHULTZ, a citizen of the United States, residing at New York, in the county and State of New York, have invented new and useful Improvements 5 in Stop-Motions, of which the following is a specification.

This invention relates to a stop-motion applicable to various machines—as, for example, sewing or tufting machines or gang-needle or quilting machines and others; and the invention resides in the novel features of construction set forth in the following specification and claims and illustrated in the annexed 15 drawings, in which—

Figure 1 is a side elevation of a stop-motion. Fig. 2 is a plan view of Fig. 1. Fig. 3 is a detail view of a modification. Fig. 4 is a plan view of another modification. Fig. 5 is a plan 20 view of another modification.

In the drawings is shown a shuttle or lock-stitch sewing-machine, although the invention is not confined to such machine. The shuttle 1 has its seat shown at 2 and is actuated by a suitable driver, such as a reciprocating slide or bar 3, with lever or actuator 4. The shuttle travels in a suitable race or space between bars or rails 5. An arm or slide 6 can move in a way formed in or along 25 a rail 5. This arm or slide 6 carries or forms part of a feeler 7. This feeler is shown perforated or in form of an eye for the engagement or passage of thread. In place of an eye shape the feeler might be differently formed—30 as, for example, hook shape, curved, or as a plain or straight finger. An eye shape has an advantage in not loosing or being able to loose the thread as long as the latter is unbroken or continuous in its passage through 35 the eye.

A lever 8, fulcrumed at 9, is connected by link 10 with a cam 11 on shaft 12. As the lever 8 is moved against arm 6 or against a shoulder or contact-point 13 on said arm the 45 latter is moved to bring the eye or feeler into such position that the needle 14 can pass down or through the goods or throat-plate. (Not shown.) When the lever is withdrawn or swung away from the arm 6, the latter 50 tends to move away from the needle under

the action of a weight 15, suitably connected to the arm 6, as by a cord or connection 16.

In speaking of a weight a spring is manifestly also understood, and conversely, since in Fig. 3 the arm 6' is shown engaged by a 55 spring 15' instead of by a weight 15.

As long as the thread engaged by eye or feeler 7 is unbroken such thread prevents the arm 6 from being moved or excessively moved by the weight 15 when released from lever 8. 60 Should such thread break and the arm 6 be freed, the weight 15 will drop into the path of the tail or arm 17 of lever 17 18, fulcrumed at 19 on a blade or reciprocating slide 20. This slide 20 acts as a carrier for the lever 65 17 18 and is reciprocated by lever 21 22, fulcrumed at 23, the lever-arm 22 being engaged by cam 24 on shaft 12. The lever-arm 18 reaches into engagement with a stud or contact part 25 on a stopping or releasing mechanism—such, for example, as a belt-shifter 70 26. When now the slide 20 carries the lever-tail 17 against the fallen weight 15, the lever-arm 18 will press on stud 25 to actuate the shifter or stopping mechanism 26.

In place of having the weight 15 contact with lever part 17 the arm 6', Fig. 3, can have a part 27 adapted to engage or contact with lever part 17 when the arm 6' is freed by the breaking of the thread.

The device is timed so that while the needle 14 descends or passes into the goods the lever 8 holds the arm 6 against the action of the weight or spring, and when the thread is drawn taut or the needle has risen the lever 85 8 is withdrawn, and the feeler 7, with arm 6, is then held by such thread against motion by the spring. This feeler 7, touching both the shuttle and needle-thread, will test both, and in case either thread is broken the consequent slackness of thread or the release of the feeler will allow the arm 6 to slide or move to position for engaging the stop mechanism. The feeler 7 when put close under the throat-plate will be at or nearly at the looping or interlocking point of the needle and shuttle threads, so as to test or feel both threads at certain intervals.

Of course the device can be modified without departing from the invention.

In Fig. 2 the arm 6 is shown moving parallel to the direction of motion of the shuttle; but manifestly the arm might be made to move at any angle to the shuttle-path, or 5 the relative direction of travel of the shuttle and arm can be varied—as, for example, in Fig. 4, where the shuttle 1' is shown adapted to travel a circular or curved path or race 5'. The feeler 7' can be pivoted, as at 28, to follow 10 the circular shuttle-path, and the arm 6' can be suitably connected to the feeler, as by a pin-and-slot connection 29 and 30, or in place of a belt-shifter, as 26, other stopping or releasing mechanism can be used, as a slide 26', 15 Fig. 5, which can be pressed by a spring or weight 31 against arm 32 of lever 32 33, so as to hold the pulley 34 against the friction disk or clamp 35, secured to shaft 36. As soon as 20 lever-arm 18 presses on stud 25' to move the slide 26' against the action of spring 31 the lever 32 33 is freed to allow the pulley 34, which is loose on shaft 36, to disengage itself from the clamp or disk 35, so that the shaft 36 and pulley 34 will no longer communicate 25 rotation to one another.

In Fig. 2 are shown a series of shuttle-races, as can be found, for example, in quilting-machines. For each shuttle with its needle there can manifestly be provided a feeler and 30 also a lever, such as 17 18, brought into play by the arm of such feeler. In Fig. 2 throats or passages 37 for the needles are shown in shuttle-race rails, and such rails have a channel or path 38 for the motion of the feeler- 35 arm 6.

The invention is of course applicable to single-needle machines as well as to gangs of needles, and the feeler 7 can be used not only in a lock-stitch machine, but also in a chain-stitch machine or double chain-stitch, such 40 as a Grover & Baker machine.

The operation of the device is readily understood. The lever or actuator 8 having moved the feeler 7 into alinement with needle 14 the point of the latter moves toward the work or throat plate to make a stitch and then returns, and when the thread running from the last stitch to the returned needle is drawn sufficiently taut—as, for example, at 45 the moment of setting the stitch—the lever 8 is withdrawn or releases the feeler 7, which is now held against the action of spring or weight 15 by such taut thread. If such thread is broken or excessively slack, the feeler 7 or 50 its arm 6 is moved by the spring or weight to engage or bring the stopping or releasing device into action. In a chain-stitch machine a breakage or improper slackness of the thread releases the feeler. In a lock-stitch or shuttle machine the breakage of the needle-thread frees the feeler, while on a breakage of the shuttle-thread the needle-thread would fail to be locked or engaged by the shuttle-thread, and such needle-thread would consequently 55 slacken to such an extent as to no longer hold

the feeler 7 against the action of the spring or weight 15 when the lever 8 is withdrawn.

The weight 15 can be prevented by a suitable stop or guide 39 from being swung laterally when struck by lever-tail 17.

What I claim as new, and desire to secure by Letters Patent, is—

1. The combination of a movable thread-feeler constructed to engage a thread, a lever arranged to engage the feeler, means for actuating said lever to hold the feeler stationary when the thread is slack, means for moving the feeler away from the thread when the latter breaks and disengages the feeler, a releasing or stop mechanism, and mechanism 80 actuated by the feeler for throwing the releasing or stop mechanism into action upon the breakage of the thread, substantially as described.

2. The combination with a thread-feeler constructed to engage a thread and a releasing or stop mechanism, of a lever arranged to engage the feeler, means for throwing said lever into engagement with the feeler and hold the latter in the thread-path when the thread is slack and throw said lever out of engagement with the feeler and release the latter when the thread is taut, a spring operating to normally move the feeler away from the thread, and means engaged by the feeler 95 when it moves away from the thread and constructed and arranged to actuate the releasing or stop mechanism, substantially as described.

3. A movable eye or thread-feeler combined with a lever or actuator for the feeler, a link and cam for causing the lever to intermittently move the feeler to the thread-path when the thread is slack and to release the feeler when the thread is tightened, a spring 100 for moving the feeler in opposition to the lever, a releasing or stop mechanism toward which the feeler moves on being released by the lever, and means, substantially as described, for securing the coöperation of the 105 feeler and stop mechanism.

4. A sewing-machine needle, and a thread-feeler, combined with a lever or actuator for moving the feeler to the needle-path, a stop mechanism toward which said feeler normally 115 moves, means substantially as described for moving the lever to carry the feeler to and hold the same at the needle-path while the needle passes through said feeler and until the needle returns and clears the feeler and 120 tightens the thread and for then moving the lever to release the feeler for allowing the latter to draw on the tightened thread so as to feel the latter substantially as described.

5. The combination with a sewing-machine, 125 of a movable feeler having an eye for the passage therethrough of the needle and thread, a lever arranged to engage the feeler to move the same and bring its eye into coincidence with the needle, means for throwing said le- 130

ver into and out of engagement with the feeler, means for retracting the feeler from the needle, a releasing or stop mechanism; and means, substantially as described, operated by the 5 feeler when the latter is retracted for throwing the releasing or stop mechanism into action, substantially as described.

6. A sewing-machine provided with a needle shuttle-race and a shuttle, a movable eye 10 or feeler, a lever or actuator for moving the feeler into position for the passage of the needle when the thread is slack and then releasing said feeler when the thread is tightened, a spring for moving the feeler away from the 15 needle, a releasing or stop mechanism, and coöperating means substantially as described between the feeler and the stop mechanism substantially as described.

7. A sewing-machine provided with a shuttle, bars or guiding-rails forming a race for 20 the shuttle, a thread eye or feeler having an arm guided by a shuttle-race rail, a lever or actuator and a spring for reciprocating the feeler-arm, and a releasing or stop mechanism 25 and coöperating means substantially as described between the feeler-arm and the stop

mechanism, said shuttle-race rail having a throat for the passage or entrance of the needle substantially as described.

8. A sewing-machine comprising a needle, 30 combined with a thread eye or feeler, a lever or actuator, a spring, and a releasing or stop mechanism toward which the feeler is moved by the spring, and coöperating mechanism 35 substantially as described between the feeler and stop mechanism, said various parts being timed with relation to one another so that the lever moves the feeler into alinement with the needle and holds said feeler while the thread is slack and the point of the needle 40 passes by and returns clear of the feeler, and the lever releases the feeler for actuation by the spring when the thread is drawn tight substantially as described.

In testimony whereof I have hereunto set 45 my hand in the presence of two subscribing witnesses.
